RAYMOND F. JAHN, OF BROOKLYN, NEW YORK

PRINTING AND STAMPING MACHINE

Original application filed April 13, 1927, Serial No. 183,318. Patent No. 1,744,770, dated January 28, 1930.
Divided and this application filed June 22, 1929. Serial No. 372,822.

This invention relates to improvements in printing and stamping machines, and has particular reference to such devices which are adapted for endorsing, cancelling, or otherwise printing upon bank checks, tickets, letters, and similar articles.

The subject matter of this invention is disclosed in my co-pending application for printing and stamping machines, filed April 10, 1927, Serial No. 183,318 but is not claimed therein, the present application being a division of the said application Serial No. 183,318.

In the above identified co-pending application, the invention has been embodied in a machine which is power-driven and capable of expeditiously operating upon a quantity of successively fed paper sheets or like articles as they are passed through a printing couple. This printing couple comprises an impression roller and a printing roller, and one of the objects of the present invention is to provide a simple and efficient driving connection for the printing couple, whereby the printing roller will be automatically rotated through a single complete revolution each time a check or other paper sheet is presented to it. For this purpose the printing roller is driven through a clutch, and controlled by a tripping mechanism which is actuated by the entering edge of a presented check. The printing roller is normally held against rotation by virtue of the engagement of a stop lever with a fixed abutment, the stop lever being pivoted on one end of the printing roller. A trip lever is also associated with the printing roller and stop lever, and is disposed in the path of the entering edge of the presented check so as to be actuated thereby, to release the stop lever and permit rotation of the printing roller. The clutch has a portion associated with the intermittently rotatable printing roller, and another portion associated with a constantly rotatable feed roller which is driven by a worm and worm gear from an electric motor. The motor shaft and worm are connected together by a flexible coupling, and the principal rotating parts are journaled in anti-friction bearings.

whereby their operation will be exceedingly smooth and efficient.

The foregoing and other objects, features, and advantages of the invention will be readily understood from the following description in connection with the accompanying drawings, wherein one form of the invention has been shown by way of illustration, and wherein

Fig. 1 is a vertical transverse sectional view through the improved printing machine;

Fig. 2 is a fragmentary vertical longitudinal sectional view through the device, showing the drive shaft coupling, gearing, and clutch;

Fig. 3 is a vertical sectional view on line 3-3 of Fig. 1 showing the normal position of the parts of the tripping mechanism, ready for operation; and

Fig. 4 is a similar fragmentary view of the tripping mechanism after the printing roller has been released.

The invention has been shown as embodied in a machine for endorsing bank checks, and in the following description, when bank checks are specified in connection with the operation of the device, it is to be understood that their equivalents may be operated upon in the same way. The device comprises a substantially flat base plate A¹, of rectangular outline and preferably having a plurality of cushion feet A² whereby to be supported upon a desk, table or the like without likelihood of damaging the surface thereof. Secured to the base plate A¹ intermediate its ends is a supporting bracket A³ having a pair of upwardly extending spaced arms A⁴ and A⁵, said arms being disposed adjacent the opposite side edges of the base plate. Also integral with the bracket A³ and extending upwardly therefrom, between said arms A⁴ and A⁵, is a shorter arm A⁶, which supports certain portions of the mechanism as will hereinafter be explained. Adjacent their upper ends, the arms A⁴ and A⁵ are provided with bearing bosses A⁷ and A⁸, respectively, having axially alined openings A⁹ and A¹⁰, in which are secured stationary mounting shafts A¹¹ and A¹², the inner ends of which are spaced from each other to rotatably sup-

port a printing roller B of the printing couple.

The printing roller B is built up of several parts, and includes a relatively thin walled 5 cylindrical shell formed of semi-cylindrical sections supported at their opposite ends by disks B³ and B⁴, which are respectively formed with outwardly extending hub portions B⁵ and B⁶ as best shown in Fig. 1. One 10 of the semi-cylindrical sections of the printing roller is preferably detachable, and provided on its outer surface with a printing or stamping die B⁹ having the desired legends B¹⁰ which, together with changeable type elements B²⁵, are used for printing upon checks 15 or other sheets as they are successively passed through the machine. Since the structural details of this roller do not form a part of this invention, a more complete description 20 of it is unnecessary.

Mounted upon the hub portion B⁶ of the mounting disk B⁴ is a ball bearing B⁴⁴ against the outer race of which rests one end portion 25 of an impression roller B⁴⁵, said impression roller being yieldably held in parallel relation to the printing roller B and having its other end portion engaging against a feed roller C¹. The feed roller C¹ is coaxial with the printing roller B and adapted to be intermittently connected therewith to rotate said 30 roller B, and is itself rotatable on anti-friction rollers C² on the mounting shaft A¹¹. Secured to the outer side of the feed roller C¹, as by screws C³, is a worm gear C⁴ which 35 meshes with and is driven by a worm C⁵ on a shaft C⁶, said shaft being journaled in ball bearings at C⁷ in a bracket C⁸. The bracket C⁸ is suspended on the mounting shaft A¹¹, as best shown in Figs. 1 and 2, and secured 40 thereto by a set screw C⁹, and the shaft C⁶ extends in a direction transverse to that of the axis of the printing roller, and forwardly beyond the bracket C⁸ for connection to a driving shaft C¹⁰ of a motor C¹¹. The shafts 45 C⁶ and C¹⁰ are substantially coaxial and connected together by a flexible coupling C¹², which has been shown as comprising a pair of disks C¹³ and C¹⁴, secured to the respective shafts C⁶ and C¹⁰, and an intermediate disk 50 C¹⁵ of flexible material. The disks C¹³ and C¹⁴ are each provided with a pair of diametrically opposed apertures C¹⁶, and said apertures of the respective disks are disposed at right angles (Fig. 2). The intermediate disk 55 C¹⁵ is provided with four apertures C¹⁷, 90° apart, and is connected to the disk C¹³ by a U shaped pin C¹⁸, and to the disk C¹⁴ by a similar U shaped pin C¹⁹. The motor C¹¹ may be of any desired type, and is secured by 60 screws to the main base A¹ and is furnished with electric current through a suitable conductor, and controlled by a manually operable switch not shown.

Novel means are employed for connecting 65 the feed roller C¹ with the printing roller B

whereby to intermittently rotate the latter one revolution at a time, said means including a clutch and a tripping mechanism. The clutch comprises a pair of semi-circular jaws D¹ and D², provided on their inner surfaces with suitable friction material D³ for engagement against the periphery of a clutch collar D⁴ which is carried by the printing roller hub B⁵. The jaws D¹ and D² are disposed within a recess C²³ in the inner end of the feed roller C¹ and are secured thereto by clamping between a pair of parallel pins D⁵, which are secured to said feed roller C¹. The opposite ends of the jaws D¹ and D² have outwardly extending lugs D⁶ and D⁷, which are apertured for the reception of a screw D⁸, said screw being fitted with a nut D⁹ against the outer side of the lug D⁶, and having a spring D¹⁰ between the screw head D¹¹ and the outer side of the lug D⁷. The spring D¹⁰ is under compression whereby to normally force the lugs D⁶ and D⁷ toward each other, and thereby cause the desired frictional engagement of the clutch lining D³ with the clutch collar D⁴, and in such condition the printing roller B will be caused to rotate with the feed roller C¹, provided said printing roller is not otherwise held against rotation. The spring D¹⁰ provides a cushioning effect against the tightening of the screw D¹¹, and also restrains said screw from turning loose. 75 80 85 90 95

Mounted upon the upper end of the stationary bracket arm A⁶, and in substantially vertical alignment with the axis of the printing roller, is a stop wheel D¹², which may 100 preferably be rotatable upon a screw D¹³. Carried by the printing roller and pivoted to the mounting disk B³ at D¹⁴ is a stop lever D¹⁵, having at its free end a roller D¹⁶ which is adapted to normally abut against the roller D¹², and thus prevent rotation of the printing roller. The stop lever D¹⁵ has its free end normally forced outwardly by a compression spring D¹⁷ which is partially disposed in a recess D¹⁸ in the hub portion B⁵, and at its other end said stop lever is provided with an arm D¹⁹ formed at its extremity with a shouldered notch D²⁰. Also pivoted to the disk B³, as at D²¹, is a trip lever D²², which has a tooth portion D²³ adapted to engage in the notch D²⁰ to maintain the stop lever in its outermost position as shown in 105 Fig. 3. The trip lever D²² is under the influence of a tension spring D²⁴ which has one of its ends connected to said trip lever at D²⁵, and its other end anchored to the roller disk B³ at D²⁶, said spring normally maintaining the tooth D²³ in the notch D²⁰. Extending outwardly from the trip lever D²² is a finger portion D²⁷, said finger portion extending 110 beyond the periphery of the printing roller B and into a groove B⁴⁷ in the impression roller B⁴⁸. Blank checks or other similar articles are 115 presented to the printing couple in the usual manner and are drawn inwardly by the con- 120 125 130

stantly rotating feed roller C¹ and the impression roller B⁴⁵, and since the finger portion D²⁷ of the trip lever is disposed in the path of said checks, it will be moved rearwardly about the pivot D²¹ disengaging the tooth D²³ from the notch D²⁰. As the stop lever D¹⁵ is thus released, the printing roller is free to rotate, the roller D¹⁶ riding over the stop roller D¹², (as shown in Fig. 4) and as rotation continues to the point where the rollers D¹⁶ and D¹² become disengaged, the spring D¹⁷ again forces the free end of the stop lever B¹⁵ outwardly, and thereafter the finger D²⁷ becomes disengaged from the entering edge of the check, permitting the return of the tooth D²³ into the notch D²⁰. The printing roller continues to rotate until it is again arrested by the abutment of the locked lever D¹⁵ with the stop roller D¹² overcoming the frictional grip of the clutch jaws D¹ and D² on the collar D⁴ and permitting subsequent slippage of said clutch jaws around the collar. This operation is repeated as each successive check is inserted and the checks are printed upon as they pass between the rollers B and B⁴⁵ of the printing couple. Because of the fact that the trip lever and the stop lever are independently pivoted upon the end of the printing roller the pressure required for releasing or tripping the mechanism will be very slight and therefore it can easily be accomplished with a thin piece of paper without injury to the same.

In using the device, the proper die plate and interchangeable type are placed in position, and the motor C¹¹ is set in motion. Quick drying ink is supplied to the printing roller from an ink well F¹ by distributing rollers F⁸ and F⁹. As the motor shaft C¹⁰ rotates, the power is transmitted through the flexible joint C¹², shaft C⁸, worm C⁶, and worm gear C⁴, to the feed roller C¹, and the impression roller B⁴⁵ is caused to rotate in the opposite direction by virtue of its contact with the periphery of said feed roller. The printing roller B, however, is normally held against rotation by the abutment of the roller D¹⁶ with the stop member D¹², the clutch jaws D¹ and D² freely slipping around the clutch collar D⁴. As the checks to be endorsed are fed, one at a time, through the printing couple, they are seized by and between the rotating feed roller C¹ and the impression roller B⁴⁵, and are carried rearwardly, their front edges striking the trip finger to release the lever D¹⁵, whereupon the clutch jaws D¹ and D² take hold of the collar D⁴ and rotate the printing roller one revolution for each check. Thus the checks are endorsed or otherwise printed upon, and are successively delivered to a suitable receiving and stacking means rearward of the printing couple. The machine is very easy running, quiet, rapid, free from vibration and compact, and the trip mechanism is so

sensitive as to be actuated by the edge of a presented check without tearing or otherwise injuring the same.

Obviously the invention is susceptible of modification in the details of construction and arrangement of parts, and the right is herein reserved to make such changes as fall within the scope of the appended claims without departing from the spirit of the invention.

Having thus described my invention, what I claim is:

1. A machine of the class described, comprising a printing roller, a fixed stop adjacent the roller, a stop lever pivoted on the roller and adapted to normally engage against said fixed stop, and a trip lever independently pivoted on the roller, said trip lever and stop lever having mutually engaging means for maintaining the stop lever in its normal position.

2. A machine of the class described, comprising a printing roller, a fixed stop adjacent the roller, a stop lever pivoted on the roller and having a free end adapted to engage the fixed stop, a trip lever independently pivoted on the roller, and means associated with the trip lever for normally maintaining the stop lever in engagement with the fixed stop.

3. In a machine of the class described, a printing roller, a fixed stop adjacent one end of the roller, a stop lever pivoted on the adjacent end of the roller and having a free end adapted to normally engage the fixed stop to prevent rotation of the roller, a latch arm associated with the stop lever, a trip lever also pivoted on the end of the roller, and means movable with the trip lever for releasably holding the latch arm to prevent disengagement of the stop lever from the fixed stop.

4. In a machine of the class described, an intermittently rotatable roller, and a tripping mechanism carried by the roller for controlling the rotation thereof, said tripping mechanism comprising a stop lever pivoted on the roller, a fixed stop adjacent to the roller for engagement by the stop lever, and a trip lever independently pivoted on the roller eccentrically with reference to the stop lever, the trip lever and the stop lever having mutually engaging means for releasably holding the stop lever against the fixed stop to prevent rotation of the roller, the stop lever being adapted to automatically pass over and disengage the fixed stop when said mutually engaging means are released.

5. In a machine of the class described, an intermittently rotatable roller, and a tripping mechanism carried by the roller for controlling the rotation thereof, said tripping mechanism comprising a stop lever pivoted on the roller, a fixed stop adjacent to the roller for engagement by the stop lever, and

a trip lever independently pivoted on the roller eccentrically with reference to the stop lever, the trip lever and the stop lever having mutually engaging means for releasably holding the stop lever against the fixed stop to prevent rotation of the roller, the stop lever being adapted to automatically pass over and disengage the fixed stop when said mutually engaging means are released, and means for automatically reengaging said releasable holding means after the stop lever has passed over the fixed stop.

6. In a machine of the class described, a printing couple including a pair of opposed rollers, tripping mechanism carried by one of the rollers, a fixed stop adjacent said rollers, and means including a clutch for rotating the rollers, the tripping mechanism comprising a stop lever pivoted on the roller, a trip lever independently pivoted on the roller, and mutually engaging means carried by the stop lever and the trip lever to releasably maintain the free end of the stop lever in the path of the fixed stop, a portion of the trip lever being disposed in the path of a sheet fed through the printing couple and being operated thereby to release the stop lever.

In testimony whereof, I have affixed my signature hereto.

RAYMOND F. JAHN.
